(57) **CLAIM**

The new design for an actuator assembly, as shown and described herein.

DESCRIPTION

FIG. 1 is a front elevation view of a first example actuator assembly of the present invention;

FIG. 2 is a first side elevation view of the first example actuator assembly;

FIG. 3 is a rear end elevation view of the first example actuator assembly;

FIG. 4 is a second side elevation view of the first example actuator assembly;

FIG. 5 is a top plan view of the first example actuator assembly; and,

FIG. 6 is a bottom plan view of the first example actuator assembly.

The broken lines in the drawings represent unclaimed environmental subject matter.
